BELT CONVEYER

Tage Georg Nyborg, Worcester, England, assignor of one-half to The Mining Engineering Company Limited, Worcester, England

Application March 11, 1936, Serial No. 68,299
In Great Britain August 27, 1935

3 Claims. (Cl. 198—204)

This invention relates to belt conveyers, more particularly to the sectional frame construction for such conveyers in which the sections consist of or incorporate a trough, the bottom of which 5 is interposed between the upper and lower run of belting.

In such conveyers, it is desirable to have the sections coupled together in such a way that limited relative vertical angular movement between them is permitted but the sections when coupled together should be laterally rigid to maintain a straight line resistant to side pressure. It is also desirable that the coupling of the sections should be made and dismantled without tools. It is an object of this invention to provide coupling means for conveyer sections having these features.

An important object of the invention is to provide coupling means for the sections of belt conveyer frames which, by the cam action between the engaging parts, automatically cause the adjacent sections to assume complete lateral alignment after the sections have been roughly engaged in approximate alignment.

A further object is to permit of relative inclination up or down from the horizontal between sections, while permitting the feet carried by the sections to seat on the floor. A further object is to utilize coupling members engaging in tapered slots at the extreme outer sides of the sections to form pivots about a horizontal axis immediately over the feet.

A further object is to provide the coupling with feet on which the conveyer may stand by extending the slotted plates (when the tapered slots open upwardly) downwardly beyond the sides of the trough.

Another object is to provide means for supporting the idle roller for the bottom run of belting in such a manner that the roller is in position when the sections are coupled together.

A typical form of construction of the coupling according to the invention will now be described by way of example with reference to the accompanying drawing, in which,

Figure 1 represents a side view of the coupling applied to sections of a belt conveyer frame,

Figure 2 is a plan of the coupling shown in Figure 1.

The conveyer frame is made up of sections 1, 2 which incorporate a trough 3. The lower run of the belt is covered by the bottom of the trough and the upper run of the belt runs therein. Plates 4 are fixed to each side at one end of the section 1 and project beyond the end of the trough.

A slot 5 is cut in the top edges 6 of the plates 4, having its sides tapering inwardly towards the bottom. The slot is preferably rounded off at the bottom.

The adjoining section 2, has plates 7 attached to its sides towards its end. The plates 7 are offset so as to have a part 8 parallel to the side 9 of the trough but spaced therefrom a distance greater than the thickness of the slotted plate 4. The part 8 of the plate 7 extends substantially to the end of the trough section 2.

Between the part 8 and the side 9 of the trough is inserted a distance piece 10, held in position by a rivet or bolt 11 passing through the side of the trough and the part 8. The radius of the distance piece 10 is preferably approximately the same as or slightly greater than the radius of the bottom of the slot in the plate 4.

The plates 4 are extended downwardly to form supports for the conveyer trough.

Inclined slots 12 are cut in the slotted plates 4 in which can be supported the idler roller 13 for the lower run of belting. When the two sections are coupled together, the mouth of the slot 12 is closed by the end 15 of the adjoining trough and the idler roller is thus locked in position.

Each section of the conveyer trough is preferably provided with a slotted plate 4 at one end and a plate 7 having a distance piece 10 at the other end.

To couple together two sections of conveyer fitted with the coupling, the end of one section 2 carrying the distance members 10 is lowered on to the end of the mating section 1 having the extended plates 4 with tapered slots 5 so that the distance members 10 enter the tapered slots 5. As the members 10 move downwards into the working position, side clearance is taken up and when fully home the conveyer sections are coupled together with lateral rigidity. To uncouple the sections the end carrying the distance members 10 is lifted up, to remove the members 10 from the slots 5.

The ends of the horizontal portions of the trough, shown in dotted lines in Figure 1, may be overlapped, as shown at 14, or in any other convenient way permitting limited vertical angularity between the sections, or may simply butt together.

In general it is desired to have the line about which adjacent sections move vertically as close as possible to the joint between the bottoms of the troughs and thus the slots and distance members are arranged as near this line as possible.

Many modifications may be made in the form of the coupling without departing from the scope of this invention.

I claim:

- 5 1. Coupling means for belt conveyer frames made in sections and each including a trough, said coupling means comprising a plate rigidly secured to each side of the terminal of one trough section, said plate extending beyond the end of 10 the section and being formed in extended portion with slots opening through the upper edge of the plates, the walls of the slots being downwardly converging and terminating in a rounded bearing portion, a plate secured to the meeting end 15 of the other section and spaced outwardly with respect to the wall of the section, and coupling members fixed in said plate and in said wall of the section inwardly of the plate, the plate on the first named section being designed to pass 20 between the plate and section wall of the second named section in the coupling of the sections, the coupling member having a diameter appropriately engaging the rounded ends of the slots for swinging support, with said diameter materially less than the maximum widths of the slots 25 at their upper ends, whereby the sections may be coupled initially by placing the coupling members within the widened upper ends of the slots in any one of several different positions, the members thereafter through the camming action of the

converging walls of the slots guiding the coupling members and thereby the section to which they are secured into proper aligned relation with the first named section, said coupling members finally seating for accurate swinging bearing relation 5 in the rounded lower ends of the slots.

2. A construction as defined in claim 1, wherein the plates in which the slots are formed are further formed with downwardly inclined slots to receive idler rollers for the belt, the edge of the 10 adjacent section having such relation to the downwardly inclined slots as to retain the idler rollers in position in the slots when the sections are coupled.

3. In a sectional belt conveyer frame, the combination of sections each including a trough, horizontal web portions of adjacent troughs overlapping at their ends to form a joint, permitting pivoting of the adjacent troughs separately about an axis in the same vertical plane as the joint, 20 horizontal coaxial pins at the sides of one end of one trough section, parts having tapered slots at the sides of the mating end of the adjacent trough section and arranged to receive the said pins, and to coat therewith to bring the sections 25 into lateral alignment the axis of the said pins when home in the slots being substantially coincident with the axis about which the adjacent troughs are separately pivotable.
